UNITED STATES PATENT OFFICE.

FRANK E. JONES, OF KIRKWOOD, ILLINOIS.

DESIGN FOR A PAPER BOX.

SPECIFICATION forming part of Design No. 28,046, dated December 14, 1897.

Application filed October 16, 1897. Serial No. 655,486. Term of patent 3½ years.

To all whom it may concern:

Be it known that I, FRANK E. JONES, a citizen of the United States, residing at Kirkwood, in the county of Warren and State of Illinois, have invented and produced a new and original Design for a Paper Box, of which the following is a specification, reference being had to the accompanying drawings, forming part thereof.

10 In the drawings, Figure 1 is a view in perspective of a paper box, showing my new design. Fig. 2 is an end view thereof.

The letter A designates the upper side, B and C the ends, and D and E the front and 15 rear sides, of the box. The upper side A is ornamented with lines to represent the dishes and table-cutlery of a dinner-table laid for four persons. The front and rear sides D and

E are ornamented with lines to represent the depending sides of a fringed table-cover. The 20 ends B and C are extended below the plane of the bottom of the sides D and E, are bifurcated at their lower edges, and are ornamented with lines to represent the depending ends of the fringed table-cover and the two 25 legs at either end of the table.

I claim—

The design for a paper box substantially as herein shown and described.

In testimony whereof I affix my signature 30 in presence of two witnesses.

FRANK E. JONES.
